UNITED STATES PATENT OFFICE

ANILLO MIJARES, OF YONKERS, NEW YORK

CARBURETOR

Application filed April 30, 1926. Serial No. 105,718.

This invention relates to carburetors of the kind used to inject a mixture of air and liquid fuel into the manifold of an automobile engine.

5 It is one of the particular objects of the invention to provide a carburetor of this kind with means which will automatically admit a very rich mixture into the manifold of the engine when starting only, eliminating separate dash controls for admission of auxiliary liquid fuel heretofore in use.

Another object is to provide a simple gravity operated check valve for the air intake end of the carburetor whereby when 15 starting only little air is drawn in, the suction in the engine manifold causing this valve to open as the amount of suction increases.

A further object is to equip the carburetor 20 or with integral means which causes water to be heated within it, the steam or vapor thereof mingling with the gas mixture to be injected into the engine for the purpose of reducing carbonization of its cylinders.

25 A still further object is to provide a structure which embodies all of the aforesaid advantages which can be most economically produced and the different units of which assembled and disassembled with the least 30 difficulty.

Other objects will become apparent in the following specification and the accompanying drawings illustrative of a preferred embodiment of my invention and in which

35 Fig. 1 is a longitudinal sectional view of the carburetor, along the plane of line 1—1 in Fig. 2;

Fig. 2 is a plan view of the same;

Fig. 3 is a sectional view through the carburetor, its upper portion taken along the plane of line 3—3 in Fig. 2, and its lower portion along the plane of line 3^a—3^a in Fig. 4;

Fig. 4 is a cross sectional view taken along the plane of line 4—4 in Fig. 3;

Fig. 5 is a cross sectional view taken along the plane 5—5 in Fig. 2;

Fig. 6 is a sectional view taken along the plane of line 6—6 in Fig. 5;

50 Fig. 7 is a diagrammatic view of the throt-

tle lever, and the lever arrangement of the carburetor with its relation to the auxiliary automatic liquid fuel valve while the engine is either at rest or running normally;

Fig. 8 is a similar diagrammatic view while the engine is being started; and

Fig. 9 is a fragmentary sectional view of the auxiliary liquid fuel valve showing the position which it assumes after the engine is started and is running normally.

Like numbers of reference denote similar parts throughout the several views and the following specification.

10 is a float chamber casing having a fuel well 11 closed by a cover 12. At the top of one side of the well is a pocket like extension 13 of the casing, substantially U-shaped in cross section, open towards the well, its outer wall 14 adapted to receive a plug 15 which is held within the pocket 13 by a correspondingly shaped extension 16 of the cover 12. The interiorly projecting end of the plug 15 is bored out at 17, the bore being reduced by a valve seat 18 to a smaller bore 19 extending partially through the plug. 20 are ducts through plug 15 at substantially right angles to the bore 19 and near its inner end. The extreme end of plug 15 is threaded at 21. Adjacent the inside of wall 14 of the casing 10, the plug 15 has two downwardly projecting spaced apart lugs 22, being bored out transversely for a fulcrum pin 23. 24 is a slot at the lower side of plug 15 between the lugs 22. Disposed over the outwardly projecting end of plug 15 is a strainer housing 25 which is of hollow square shape, its side adjacent the wall 14 being bored out to fit over the diameter of the plug snugly and its opposite side bored out at 26 somewhat larger in diameter to enable a cylindrical strainer 27 to be placed within it and over the cross ducts 20. The lower side of the strainer housing 25 is provided with a tubular extension 28 tapped interiorly for a liquid fuel supply pipe 29. 30 is a nut which has an extension 30^a to fit the enlarged bore 26 of the housing 25. Nut 30 is adapted to fit tightly the plug 15 within the wall 14 of the casing by clamping lugs 22 against the inner side of wall 14 and the strainer housing

25 against the outer side of wall 14, the plug being held against vertical displacement by the cover 12. 31 is a fuel valve laterally disposed within the plug 15 having a large end 32 pointing toward the fuel well, valve face 33 being adapted to make a tight joint with seat 18, and a guide 34 fitting loosely within bore 19. Large end 32 of the valve 31 is flattened at 34^a and is provided with a small blind orifice 35. 36 is a substantially L-shaped lever, being fulcrumed at the junction of its two legs onto the pin 23. The short leg 37 is fitted loosely between the two lugs 22 of the plug 15 and extends within the orifice 35 of the valve 31. At the end of the long leg 38 of the lever 36 is loosely suspended a float 39. The details of the fuel inlet mechanism, just described, are claimed in another copending application, Serial 10 #142,654, filed by me on October 19, 1926.

15 At one side of the casing 10, substantially at right angles to the plug 15, the casing has an extension 40. 41 is a horizontally disposed duct at the lower part of the extension, communicating with the bottom of the float chamber 11. 42 is a vertically extending passage from the duct 41 in communication with a horizontal outlet passage 43 near the top of the extension 40. 44 is another vertical passage, substantially parallel to 42 and located between 42 and the chamber 11. Passage 44 connects bottom duct 41 with outlet passage 43. 45 is a restricted opening having a valve seat for a main liquid fuel needle valve 46 which extends through passage 44 and is threaded above passage 43 in the extension 40 at 47. 48 is a knurled handle knob of the stem 46. The lower end of passage 42 is threaded at 49 to receive a plug 50 which has a restricted opening 50^a with a valve seat 50^b for an auxiliary liquid fuel needle valve 51 which is in threaded engagement with the lower end of passage 42 which is closed fluid-tightly by a packing nut 52 around the valve 51. 53 is a knurled handle knob of the valve 51. Passage 42 is restricted above plug 50 immediately adjacent outlet passage 43 to form a valve seat 54. 55 is an automatic auxiliary liquid fuel valve having a stem 56 slidably mounted within extension 40 above outlet passage 43, the stem 56 being reduced somewhat where it projects through the restricted opening adjacent the valve seat 54 and is enlarged at 57 below this opening to engage the seat 54. In the normal position shown in Fig. 1, the automatic valve is suspended from an upwardly extending projection 58 of the extension 40 by a circular plate 59 riveted to the stem 56. In this position, the restricted opening adjacent valve seat 54 is not closed by the valve face 57 which extends somewhat below the seat. Screwed into extension 40 at 60 in line with outlet passage 43 is a shank 61. A vent valve 62 having a screw threaded stem 63 and a

knurled handle knob 64 engages an extension 65 at the top of the shank 61 adjacent extension 40. 63^a is a groove at one side of the screw threaded stem 63 terminating somewhat below the knob 64. 66 is a bore in shank 61 in line and communicating with outlet passage 43. The shank 61 is reduced in diameter from the extension 65 at its top to its end at 67, its extreme end being threaded at 68 to receive a nut 69. 70 is an outlet opening at one side of the reduced portion 67 of the shank 61 communicating with bore 66.

70^a is a mixer housing of substantially cylindrical shape, consisting of a top casing 71 and a bottom casing 72, both cup-shaped, their open ends bolted together by bolts 73 extending through lugs 74 and 75, respectively, forming part of the top casing and the bottom casing. At one side of the top casing 71 is a tubular extension 76 having fastened within it an air pipe 77 secured thereto by a set screw 78. The extension 76 projects somewhat inside of the top casing 71 and terminates there to form a slanting annular valve seat 79, its bottom projecting into the casing further than its top. A check valve 80 consisting of a flat disc is hinged to the top casing 71 adjacent the top of the valve seat 79, at 81. Owing to the slant of the valve seat 79 it is obvious that normally the check valve 80 contacts with the seat 79 closing the inlet opening which it surrounds. Rearwardly extending from the top casing 71 is a manifold connection 82 consisting of a circular branch 83 and a flange 84 provided with bolt holes 85 for suitably fastening it to the manifold of an automobile engine. 86 is a round passage through manifold connection 82 communicating with the inner part of top casing 71 and the engine. 87 are bosses at both sides of the branch 83 bored out to suit reduced end 67 of shank 61 which is clamped tightly against them by nut 69 in such a manner that its outlet 70 is located in the center of passage 86 facing the engine.

110 Mounted vertically in the branch 83 between shank 61 and flange 84 is a rotatable shaft 88 extending through the passage 86. 89 is a butterfly valve secured to shaft 88 within the passage 86 for the purpose of regulating its opening. On the top of the shaft 88 above branch 83 is fastened a hub 90 having a lever 91 extending forwardly thereof, terminating in an eye 92 for suitably connecting this end with the throttle lever of an automobile engine. 93 is another lever integrally connected to hub 90 in angular relation to lever 91 forming a V therewith. Lever 93 is somewhat longer than lever 91 and is substantially T-shaped having a flat head 94 at its extreme end. The relation of head 94 of lever 91 to the circular plate 59 of the automatic liquid fuel valve 55 is such that it is about $\frac{1}{8}$ " to $\frac{1}{4}$ " away from the same while the engine is at rest, the position shown in

75

Figs. 1 and 2. But when the throttle lever, in starting the car, is moved forward about an inch, the position of the head 94 will be immediately above that of the plate 59, as indicated in dotted lines in Fig. 2. The butterfly valve 89 is so adjusted on shaft 88 that in normal position it is slightly open. 95 is a post on top of branch 83 and adjacent top casing 71 adapted to receive a set screw 96 in its upper part for the purpose of adjusting the normal position of lever 91 and thereby the opening of the butterfly valve 89.

The bottom casing 72 is provided with jacketed sides 97 and bottom 98 forming a heating chamber 99. 100 is a connection at the lower side of bottom casing 72 to receive an exhaust inlet pipe 101 permitting exhaust from the engine to enter the heating chamber 99, and 102 is a similar connection at the bottom furthest removed from connection 100 for an exhaust outlet pipe 103 of smaller size than inlet pipe 101. 104 is a water float chamber at a side of bottom casing 72, its top being closed by a suitable cover 105, and having a restricted opening 106 at its bottom, a valve seat 107 immediately adjacent and below the said opening 106, and a connection 108 into which is threaded a water supply pipe 109. 110 is a valve stem adapted to be inserted into chamber 104 through opening 106 and has an enlarged bottom end tapered to seat against valve seat 107. The upper end of the stem 110 is threaded to receive a metal float 111 which may be adjusted upon the stem by its thread. 112 is a duct from the float chamber 104 to the inside of the bottom casing 72 surrounded by the heating chamber 99. 113 is a metal plate, clamped between top casing 71 and bottom casing 72 which has a restricted opening 114 in its center and downwardly extending flanges 115 surrounding the opening.

The operation of the device is as follows:

Fig. 1 shows the position of the carburetor before starting the car. The fuel well 11 is filled with liquid fuel which passes, as is clearly shown in Fig. 5, through pipe 29, strainer 27, ducts 20, past valve 31 into the well, the float being raised as soon as the liquid fuel reaches a predetermined level, when the short leg 37 of lever 36 pushes the valve 31 against its seat 18, shutting off the supply of liquid fuel, until the float 39 drops sufficiently to again open the valve 31. Liquid fuel also partially fills the vertical passages 42 and 44 which communicate with the fuel well 11 by duct 41. The position of a throttle lever 116 before starting is indicated diagrammatically in Fig. 7. Throttle lever 116 is mounted rotatably upon a suitable guide 117 as is well known in the art. In this position which conforms to the plan view shown in Fig. 2, the head 94 of the lever 93 clears the plate 59 of automatic valve 55 which is suspended above extension 58 by plate 59, so as to keep open the

restricted opening adjacent valve seat 54 of the passage 42, as clearly shown in Fig. 1. In starting, the throttle lever is advanced about an inch, as shown diagrammatically in Fig. 8. In this position, liquid fuel from

the fuel well 11 is drawn into the manifold by the suction of the cylinders of the engine through duct 41, opening 45, passage 44, and also opening through plug 50, passage 42,

past valve seat 54, into the common outlet 70 passage 43, thence through bore 66 of shank 61 from the outlet 70, past butterfly fly valve 89 into the manifold of the engine. Head 94, immediately above plate 59, keeps the auxiliary valve 55 open, that is, limits its upward

travel and prevents it from contacting with its seat 54, whereby liquid fuel is drawn in from the passage 42 into the outlet passage 43, or in other words, while in this position, liquid fuel is drawn into the engine past the

main liquid fuel valve 46 and the auxiliary liquid fuel valve 55. Simultaneously air is drawn in through the air inlet pipe 77, the amount of air, however, is restricted by check valve 80 which only opens partially until the

engine has attained its full speed, so that the mixture introduced into the manifold is at this time a very rich one. As soon as the engine has reached its full speed and is thoroughly warmed up, the throttle lever is returned to the position shown in Fig. 1 and

Fig. 7 and the gas controlled by the foot accelerator, as is well known in the art. When running at full speed or normally after being warmed up, it is advisable and most economical to inject into the engine a mixture considerably leaner than when starting. I accomplish this automatically in the following manner.

55 is a floating valve, downwardly suspended by plate 59 and kept from its seat 54 by gravity, affording communication between outlet passage 43 and vertical passage 42. After the engine is now running and the

throttle lever is returned to its original position, whereby the head 94 of lever 93 again clears the plate 59, the suction effect of the engine and the momentum of the liquid fuel rushing through outlet passage 43 and passage 42 and the opening between the two passages controlled by the valve 55, forces this

valve to its seat 54, entirely closing off communication between passages 42 and 43, so that liquid fuel can be drawn into the manifold only past the main liquid fuel valve 46.

Attention is particularly called to the fact that the head 94 in the starting position prevents the closing of valve 55 in the manner just described, because the lateral travel of this head and its position when starting is immediately above that of plate 59 which

contacts with the underside of head 94 in such a manner as not to shut off communication between passages 42 and 43, as indicated in dotted lines in Fig. 1. Just as soon as the head 94 is removed from above the plate 59

extension 58 by plate 59, so as to keep open the

of the valve 55, this valve will be carried upwardly by the liquid fuel and the suction of the engine and shut off passages 42 and 43 from each other and restrict the supply of liquid fuel to that drawn in past the main liquid fuel valve 46 only. The amount of liquid fuel drawn in past the automatic valve 55 when starting may obviously be regulated by auxiliary needle valve 51. After the engine has been started and the auxiliary valve 55 is closed, as is shown in Fig. 9, its plate 59 is located above the line of travel of head 94 of the lever 93, so that, when the engine is sped up by the foot accelerator, the head 15 travels below the plate 59. As soon as the engine stops running, the auxiliary valve 55 will open again by gravity. The vent valve 62 serves simply to disrupt the flow of liquid fuel after the engine is stopped to prevent 20 siphoning.

In cars not equipped with this automatic device for admitting a rich mixture into the engine when starting, an auxiliary liquid fuel valve was usually opened by independent manipulation of its control mechanism commonly attached to the dashboard of the automobile. I eliminate such devices entirely and admit the rich mixture when starting only and automatically reduce the same to a lean 25 one, as soon as the throttle lever, after the engine is started, is returned to its original position.

In order to thoroughly mix the air and liquid fuel and to heat the mixture just before 30 entering the engine, I admit water or any other liquid from the radiator or other suitable source of supply by way of pipe 109 into the water float chamber 104. The float 111 is so adjusted upon stem 110 that a predetermined constant level of water is maintained within the chamber and the bottom casing 72 of the mixer housing with which chamber 104 communicates through duct 112. Should the level of water drop, the float operated valve 110 will drop also and admit additional water until the valve opening 106 is again closed. The water within the bottom casing is heated by the exhaust entering the heating chamber 99 through pipe 101. 35 Exhaust outlet pipe 103 is smaller than the inlet pipe 101 which sufficiently retards the travel of the exhaust through the chamber which surrounds the water in the bottom casing, so as to heat the water quickly. Plate 113 above the water reservoir within the bottom is provided with the restricted opening 114 and downwardly turned flanges 115 to confine the water within the bottom of the mixer housing and avoid splashing of the 40 same into its upper parts, and the restricted opening has the further tendency to build up a slight pressure within the water reservoir below it. All of this causes the water to vaporize quickly and its steam to saturate the 45 air drawn in through valve 80 and give the

same sufficient moisture to thoroughly mix with the liquid fuel. The small quantity of steam carried into the cylinders will eliminate the formation of carbon, so that the power of an engine using this particular feature is much increased over engines without it.

Besides the operating characteristics just described, the structure herein disclosed, presents certain advantages of design whereby the same can be assembled and taken apart for repairs or inspection very simply and quickly. The entire valve mechanism of the liquid fuel float chamber is carried by the plug 15 which can be assembled separately and then attached to the float chamber casting by simply tightening nut 30. Simply disconnecting nut 30, after the cover 12 has been removed, permits the taking out of the entire valve unit and float. Similarly the entire float chamber casing and all of its liquid fuel valves, including the auxiliary valve and vent valve, may be assembled in unit form and then by simply pushing shank 61 through branch 83 of the manifold connection, the nut 69 will securely attach this unit thereto. Furthermore, by having these units separately from the manifold connection, and the manifold connection with the top casing of the mixer housing an integral unit, by changing this unit only to suit various makes of cars in size and location of manifold connection, the carburetor can be manufactured very economically in quantity production.

While I have shown and described a preferred embodiment of my invention, I do not wish to limit myself to the particular construction disclosed. It is obvious that various changes of form, proportion, minor details and combination of parts may be resorted to without departing or sacrificing any of the advantages of the invention, as defined in the appended claims.

What I claim as new, is:

1. In a carburetor for gas engines with a throttle lever control, having a float controlled liquid fuel supply, a main liquid fuel valve, an auxiliary liquid fuel check valve, means for preventing closing of the said auxiliary check valve when the throttle lever of the engine is advanced to starting position, the said auxiliary valve being adapted to close automatically by the suction in the engine and the momentum of the liquid fuel in line of travel of the said auxiliary valve as soon as the throttle lever of the engine is returned to its normal position after starting, an air connection to the carburetor, and a hinged swing check within the carburetor adapted to adjust automatically the amount of air admitted into the carburetor in proportion to the speed of the engine.

2. In a carburetor for gas engines with a throttle lever control, having a float con-

- trolled liquid fuel supply, a main liquid fuel valve, an auxiliary liquid fuel check valve, means for preventing closing of the said auxiliary check valve when the throttle lever of the engine is advanced to starting position, the said auxiliary valve being adapted to close automatically by the suction in the engine and the momentum of the liquid fuel in line of travel of the said auxiliary valve as soon as the throttle lever of the engine is returned to its normal position after starting, an air connection to the carburetor, a hinged swing check within the carburetor adapted to adjust automatically the amount of air admitted into the carburetor in proportion to the speed of the engine and means within the carburetor to create and introduce steam into the air prior to mixing with the liquid fuel.
- 20 3. In a carburetor, the combination of a mixing chamber for air and liquid fuel and a water chamber below the mixing chamber, the said water chamber having jacketed side and bottom walls forming a heating chamber, exhaust piping from an engine connected to the said heating chamber, and a partition with a restricted opening having downwardly extending flanges between the said mixing and water chambers for the purpose of providing an unobstructed passage for steam created within the said water chamber to the said mixing chamber.
4. In a carburetor, the combination of a mixing chamber for air and liquid fuel and a water chamber below the mixing chamber, the said water chamber having jacketed side and bottom walls forming a heating chamber, exhaust piping from an engine connected to the said heating chamber, and means to supply water at a predetermined level to the said water chamber comprising a float chamber in communication with the said water chamber, having a water connection, a float, and a valve adjustably secured to the said float adapted to shut off the said water connection when the water in the said water chamber has reached its predetermined level, all for the purpose of admitting steam into the mixing chamber to saturate the air.
- 50 In testimony whereof I have hereunto set my hand.

ANILO MIJARES.
